UNITED STATES PATENT OFFICE.

JAMES R. CARMER, OF WILMINGTON, DELAWARE, AND CHARLES O. KEAGY, OF PHILADELPHIA, PENNSYLVANIA.

RAILWAY CARD-HOLDER.

1,102,869.

Specification of Letters Patent.

Patented July 7, 1914.

Application filed July 14, 1913. Serial No. 779,033.

To all whom it may concern:

Be it known that we, JAMES R. CARMER and CHARLES O. KEAGY, citizens of the United States, residing at Wilmington and 5 Philadelphia, respectively, in the counties of New Castle and Philadelphia and States of Delaware and Pennsylvania, respectively, have invented new and useful Improvements 10 in Railway Card-Holders, of which the following is a specification.

This invention has reference to railway card holders of the general type shown and described in our prior application, Serial Number 692,973, filed on or about April 24, 15 1912.

It comprehends certain hereinafter described improvements in or relating to the construction and mounting of the holder, whereby the latter, when fastened to the 20 car, will be so disposed as to provide a gradually increasing space between its top and bottom edges and the car wall, which effectually prevents the accumulation of snow, ice or water and, also, of cinders 25 upon the top of the holder and their subsequent entry into the interior of said holder.

An embodiment of the invention is illustrated in the accompanying drawing, whereof:—

30 Figures 1 and 2 are, respectively, a perspective view and a transverse vertical section of the improved holder, the cover part or element being shown in Fig. 1 as open, and in Fig. 2 as closed.

35 As shown in said drawing, the holder consists of two main elements or parts, namely; a body portion, or body 1, and a cover 2 therefor. Both elements may be of any desired size and general shape, and are preferably constructed of pressed sheet metal.

The body 1 comprises a flat plate or base 3 provided at its several marginal edges with continuous, outwardly projecting flanges 4, 5, 6 and 7, the top flange 4 having 45 a slight upward inclination, as shown in Fig. 2. This element is designed for attachment by means of screws 8, or the like, to the particular point on the car 9 prescribed by the Master Car Builders' Association, or other governing body.

50 The companion element, *i. e.*, the cover 2, comprises, in like manner, a plate 10 having marginal flanges 11, 12, 13 and 14, which project inwardly for coöperation with the corresponding body flanges to prevent the

entrance of water, snow and cinders into the interior of the holder when the cover is closed. The width of the top flange 11 is approximately half that of the side and bottom flanges 12, 13 and 14. The elements 1 and 2 are pivotally connected at their upper ends by means of pins 15, or the like, which pass through registering openings in the side flanges 5 and 12, and 6 and 13, and thus permit the cover to be swung upwardly into 60 open position, this upward movement being terminated by the contact of the narrow cover flange 11 with the inclined body flange 4, as shown in Fig. 1.

As originally stated, it is the purpose of 70 our invention to so dispose the holder that, when attached to the car wall, a space will be left or produced between the latter and the base plate 3 which gradually increases from its upper to its lower end. This result is obtained, preferably, by providing the aforementioned plate 3 with two series of rearwardly-extending lugs, bosses or like 75 projections or feet 16 and 17, the upper feet 16 being somewhat shorter than the lower 80 feet 17, so that when these feet are in contact with the car wall, the lower portion of the holder will be disposed a greater distance away from said wall than the upper portion thereof, the holder then occupying 85 the position represented in Fig. 1. Certain of the feet are formed with central apertures 18 through which the screws or other fasteners 8 are passed, the heads of said fasteners being received in the cavities or 90 seats produced by the formation of the feet.

The two main parts or elements of the holder are normally locked together by means of a latch device which is here shown as of the snap type and as comprising a 95 rib-like male member 19 provided on a yielding or resilient tongue 20 that forms a portion of the bottom body flange 7, and an elongated groove-like female member 21 provided upon the bottom cover flange 14. 100 The tongue 20 is produced by forming a pair of transverse slits in said flange 7, and then crimping or corrugating the portion between the slits to form the rib 19, while the socket 21 is stamped or pressed out 105 from the flange 14, the parts 19 and 21 being so proportioned that the former will snap into the latter when the cover is closed. To open the holder, a finger piece or handle 22 is provided, said finger piece being pref- 110

erably located upon the flange 14 and produced by slitting that flange and bending the portion thereof between the slits laterally outward.

5 The cards, (not shown), are retained within the body of the holder by suitable devices which may advantageously consist of barbs 23, or the like, upon which the cards are impaled. A pair of these impaling devices are depicted in Figs. 1 and 2, as stamped from the plate 3 and bent outward into approximately horizontal position, their free ends projecting, when the cover is closed, into recesses 24 which are produced by indenting said cover at the proper points.

10 In the appended claims, reference is made to the back and the top member of the holder. The back of the holder is obviously the plate 3 of the body element, while the top is constituted, in effect, by the flange 4 on that element, the top flange 11 of the cover element having a width which is much less than that of the flange 4, as previously stated. Also, since the flange 4 is inclined upwardly and forwardly, it will constitute a chute which discharges any water, snow or cinders which may fall thereon into the upper portion of the space between the holder back and the car wall.

15 The invention, its manner of use, and its advantages are believed to be apparent from the foregoing, and further description thereof is accordingly omitted.

20 35 What is claimed is:—

1. A railway card holder for attachment to car walls having its back provided adjacent the top and bottom edges thereof with rearwardly-projecting feet adapted to contact with the car wall, to dispose said back away from said car wall when the holder is attached thereto, the lower feet having a greater length than the upper feet, whereby the distance between the lower portion of the holder back and the car wall is greater than that between the upper portion of said back and said car wall.

25 40 45 50 55 2. A railway card holder for attachment to car walls comprising pivotally-connected body and cover elements, the back of said body element having its inner face indented adjacent the upper and lower edges thereof, to form rearwardly-projecting feet adapted to contact with the car wall, to dispose said back away from said car wall when the

holder is attached thereto, the lower feet having a greater length than the upper feet, whereby the distance between the lower portion of the holder back and the car wall is greater than that between the upper portion of said back and said car wall.

3. A railway card holder for attachment to car walls comprising pivotally-connected body and cover elements, the back of said body element having its inner face indented adjacent the upper and lower edges thereof, to form rearwardly-projecting feet adapted to contact with the car wall, to dispose said back away from said car wall when the holder is attached thereto, the lower feet having a greater length than the upper feet, whereby the distance between the lower portion of the holder back and the car wall is greater than that between the upper portion of said back and said car wall, certain of said feet being apertured to permit the fastening devices to be passed therethrough.

4. A railway card holder for attachment to car walls having its back provided with upper and lower rearwardly projecting feet adapted to contact against the car wall, to dispose said back away from the car wall when the holder is attached thereto, the lower feet having a greater length than the upper feet, whereby the space between the lower portion of said back and the car wall is greater than that between the upper portion of said back and said car wall, the top member of said holder being inclined upwardly and forwardly, to discharge water, snow and cinders falling thereon into the space between said back and car wall.

5. A railway card holder for attachment to car walls having its back provided with upper and lower rearwardly projecting feet adapted to contact against the car wall, to dispose said back away from the car wall when the holder is attached thereto, the top member of said holder being inclined upwardly and forwardly, to discharge water, snow and cinders falling thereon into the space between said back and car wall.

In testimony whereof we have hereunto set our hands in presence of two subscribing witnesses.

JAMES R. CARMER.
CHARLES O. KEAGY.
